UNITED STATES PATENT OFFICE.

LUDWIG DÜRR, OF FRIEDRICHSHAFEN-ON-THE-BODENSEE, GERMANY, ASSIGNOR TO
THE FIRM: LUFTSCHIFFBAU ZEPPELIN GESELLSCHAFT MIT BESCHRÄNKTER HAF-
TUNG, OF FRIEDRICHSHAFEN-ON-THE-BODENSEE, GERMANY.

AUXILIARY DEVICE FOR ASSEMBLING AIRSHIPS.

Application filed September 3, 1921, Serial No. 498,574, and in Germany September 10, 1920.

My invention relates to an auxiliary device for assembling airships and more particularly rigid airships.

The frame of an airship comprises rings which at certain distances are connected by longitudinal girders so as to form the body of the airship. The rings are assembled on the ground, braced, erected and assembled to the body.

As the rings are not rigid, it is very difficult to erect and assemble them, so that an auxiliary device or jig is necessary. The conditions which such a jig must fulfill, are very severe. Above all, it should be light and rigid and at the same time afford the greatest possible accessibility to the rings.

According to my invention, the jig for transporting and assembling transverse girders, rings and longitudinal girders comprises two concentric rings connected to form a panel work, which rings are connected with a second pair of rings to form a frusto-pyramidal skeleton.

The jig is made of wood, light metal, or high grade steel shapes. By means of it, the airship body can readily and rapidly be assembled and any undue stressing of the rings is avoided.

The rings are, as heretofore, assembled from shapes on the ground, then engaged by the jig and erected or brought to the place of assembly. Here, the rings with the jig are raised by a crane running on rails suspended from the roof girders of the shed and brought to that end of the body where it is to be assembled. The jig remains connected with the ring until the longitudinal girders have been assembled.

A plurality of rings may be attached to a jig.

It is important that the jig should be able to adapt itself to the various ring diameters of an airship. With this object in view, brackets are formed on the jig or a further ring is secured to it.

A suitable construction of the jig is the form of a ring, the form of a trapeze as the cross-section of the ring having the advantage that the one front edge has a great surface in combination with lightest weight so that rings of widely varying diameters may be attached to the jig.

Preferably, the base of the frusto-pyramidal jig is composed of concentric polygons

which are adapted to the shape of the airship's body.

In the drawings affixed to this specification and forming part thereof, two modifications embodying my invention are illustrated diagrammatically by way of example.

In the drawings

Figs. 1 and 2 are an elevation and end view, respectively of a prismatic, and

Figs. 3 and 4 are similar views of a frusto-pyramidal jig, but partly broken up.

Figs. 5 and 6 are elevation and front views, respectively, of a jig like that of Figures 3 and 4 but with radially extending supports reaching outwardly from the main structure of the jig, thereby making it serviceable for larger rings.

Fig. 6 is partly broken up.

Figs. 7, 8 and 9 are side views of the hull of an airship in state of erection. In Fig. 7 the jig *j* is in horizontal position with rings *r* attached to it. The arrow shows the movement of the lower end of pulley *z* which will bring jig and rings in upright position. In Fig. 8 this vertical position is attained and the arrow indicates that jig and rings have still to be lifted until the ring most to the left is in proper position for assembly to the hull structure *H*.

Fig. 9 shows how this ring is connected to the longitudinal girders of the hull whereafter the stiffening effect of the jig becomes superfluous.

Referring now to Figs. 1 and 2, the jig comprises two outer rings *a* and two inner rings *b* which are combined to form an annular skeleton by rods *c* and bracings *d*. To this skeleton, the several rings are secured by ropes or other suitable means. The rings are secured to the skeleton at the place where they are assembled.

The jig serves for carrying the rings to the place of assembly. In Fig. 1 it is shown suspended from a pulley *g* on a rail by means of ropes *f*. The jig is driven toward the end of the airship body *i* as indicated by the arrow where the rings are assembled and connected by longitudinal girders *k*.

Referring now to Figs. 3 and 4, the jig is frusto-pyramidal in shape and comprises two pairs of rings *l* and *m* which are connected by radial and axial rods *n* and braces *o*. For rings of greater diameter, for instance, those at the central portion of the air-

ship, supports *p* may be attached to the outside of the jig, which may either be independent brackets or the like or may be combined to form a skeleton, as shown in Figs. 5 and 6. *r* are the rings to be assembled which, as in the modification illustrated in Figs. 1 and 2, may be secured to the jig by any suitable means such as ropes or straps.

I wish it to be understood that I do not desired to be limited to the exact details of construction shown and described, for obvious modifications will occur to a person skilled in the art.

I claim:

15 1. Assembling device for the rings of airship hulls, comprising two pairs of concentric rings, stays and bracing wires connecting said rings to form a panel-work frame.

20 2. Assembling device for the rings of airship hulls, comprising two pairs of concentric polygonal rings and stays and bracing

wires uniting said rings to form a panel-work frame of frusto-pyramidal diagonal section.

3. Assembling device for the rings of airship hulls, comprising two pairs of concentric rings, stays and bracing wires connecting said rings to form a panel-work frame, and brackets fitted to the circumference of said rings, so as to enlarge them.

4. Method of assembling the hull of a rigid airship, which consists in first assembling a ring in a substantially horizontal plane, in fastening said ring temporarily to a jig which is safe against distortion, in erecting said jig together with said ring into substantially vertical position, in connecting said ring to the longitudinal girders of said hull, and in disconnecting said jig from said ring.

In testimony whereof I affix my signature.

DR. LUDWIG DÜRR.
